UNITED STATES PATENT OFFICE.

HENRY J. WARD, OF INDIANA HARBOR, INDIANA, ASSIGNOR TO BARLOW C. DICKEY,
OF INDIANA HARBOR, INDIANA.

CAR-SEAL.

1,108,953.

Specification of Letters Patent.

Patented Sept. 1, 1914.

Application filed August 23, 1913. Serial No. 786,269.

To all whom it may concern:

Be it known that I, HENRY J. WARD, a citizen of the United States, and resident of Indiana Harbor, county of Lake, and State of Indiana, have invented certain new and useful Improvements in Car-Seals, of which the following is a specification, and which are illustrated in the accompanying drawings, forming a part thereof.

10 The invention relates to car seals and more particularly to those of the type known as automatic seals and comprising a chambered head and a shackle and provision for securing an end of the shackle within the chamber of the head in such a manner that it cannot be withdrawn without destroying the seal.

20 The object of the invention is to provide improved means for preventing the insertion of a cutting tool into the chamber of the head along the path of the shackle and thus opening the seal by severing the locking instrumentalities.

25 To this end the invention contemplates the use of abutting transverse shoulders formed upon a wall of the head and upon the shackle and in order that these shoulders may be effective in preventing the insertion of a cutting tool, the invention further contemplates a form of locking means constructed to hold the end of the shackle in fixed position within the chamber of the head.

30 In the accompanying drawings, Figure 1 is a central longitudinal sectional view of a seal embodying the features of improvement provided by the invention, the parts being shown in closed position; Fig. 2 is a detail plan view showing a blank of sheet metal from which the parts of the seal may be formed; Fig. 3 is a detail plan view of the head of the seal; Fig. 4 is a transverse sectional view taken on the line 4—4 of Fig. 1, Fig. 5 is a detail perspective view showing 45 the end of the shackle, and Fig. 6 is a detail perspective view showing a modified form of an end of the shackle.

40 The seal is conveniently formed from a single piece of sheet metal, as 10. This sheet metal blank may be transversely folded upon the lines $x-x$ and $y-y$ to provide a chambered head, 11, a tongue 12 within the chamber of the head and a strap or shackle 13. When formed in this way the end 45 of the chambered head 11, is left open for

the insertion of the free end of the strap, 13, when the seal is to be closed. The margins of the parts, as 15 and 16, which form the base and cover plates respectively of the chambered head, 14, are interfolded as indicated at 31, 32, Fig. 4.

50 In carrying out the invention, the part 16, forming the cover plate of the chambered head 14, is depressed for a portion of its length, forming a longitudinal channel, 17. The part forming the tongue, 12, is similarly depressed to form a channel 18, which receives the depressed portion 17, of the cover plate 16. The end of the channeled portion 18, of the tongue 12, provides an outwardly facing transverse shoulder, 19, extending part way across the chamber of the head. For engagement with this shoulder, a part of the strap, 13, adjacent its free end is depressed in the form of a channel 20, the inner end, 21, of the channel being in the form of a transverse shoulder extending part way across the strap and abutting against the transverse shoulder 19 when the end of the strap is thrust into the chamber of the head. The side portions 22, 23 of the strap fit against the under side of the tongue 12, at each side of its channel 18.

55 Any convenient means may be employed for locking the end of the strap within the chamber of the head. Preferably this will take the form of a shoulder, 24, struck upwardly from the floor of the channel, 20, of the strap, in position for engagement with the end of the tongue, 12. To insure the shoulders 19 and 21 being held in contact when the seal is closed, the shoulder 24 is so positioned as to just pass the end of the tongue 12, when the shoulder 21, comes into engagement with the shoulder 19. The free 60 end of the tongue 12 is downwardly curved for engagement with the shoulder 24, the location of the end of the tongue in the path of the shoulder being insured by depressing a part of the floor plate, 15, to provide a 65 pocket, 25, for receiving the end of the tongue and by sufficiently curving the tongue to cause its end to elastically enter this pocket until the insertion of the end of the strap. The contacting shoulders 19 and 21 serve to effectually prevent the insertion of a tool over the strap 13, for raising the tongue 12, out of engagement with the shoulder, 24. Similarly the formation 70

75 of the shoulder 24 upon the floor of the chan- 75

neled portion 20 of the strap, insures that the engagement of the tongue with the shoulder cannot be disturbed by the insertion of a tool either below or about the sides 5 of the strap. The engagement of the tongue, 12, with the shoulder 24, when the shoulders 19 and 21 are in contact, firmly holds the end of the strap against longitudinal play within the chamber of the head. The 10 passage of any hooked form of tool beyond the end of the strap is thus prevented. While the tongue, 12, is desirably of such length as to engage the shoulder, 24, when the shoulders, 19 and 21, are exactly in contact, it will be understood that when the seal 15 is to be formed by automatic machinery the parts will be so proportioned as to permit the shoulder 24 to pass a short distance beyond the end of the tongue, 12. This is 20 for the purpose of preventing slight differences in the proportions of the parts which may occur from interfering with the operation of the seal.

In order that cutting through the tongue 25 at the shoulder, 19, by the insertion of a cutting tool above the strap, 13, may not serve to open the seal, the margins of the tongue, 12, are preferably interfolded with the margins of the base and cover plates, 30 15, 16 of the head. As shown, the tongue, 12, is provided with lateral projections, 26, 27, and the margins of the cover plate 16, of the head are provided with notches 28 and 29. When the parts are folded together 35 upon the line α — α , the projections 26 and 27 enter the notches 28 and 29, respectively, and are interfolded with the margins of the floor plate 15. As the base of the tongue, 12, must be separated from the floor plate 15 40 of the head a sufficient distance to permit the shoulder 24 to pass between these parts, a rib, 30, is preferably struck up from the floor of the channeled portion 20 of the tongue to fill the space between these parts 45 when the seal is closed. If desired, this space may be filled by raising the floor of the channel 20 throughout a portion of the length of the channel for its entire width, as indicated at 33 in Fig. 6.

50 I claim as my invention,

1. In a car seal, in combination, a chambered head having top and bottom walls and an open end, one of the said walls of the head being longitudinally channeled for a 55 portion of its length only to provide an outwardly facing transverse shoulder extending only part way across the said wall intermediate its ends, a strap adapted to enter the chamber of the head through its said open 60 end, the strap being channeled to provide a transverse shoulder complementary to the said shoulder on the wall of the head, and a coöperating spring tongue and stop shoulder, one of said parts being mounted in the 65 chamber of the head beyond the said trans-

verse shoulder on the wall of the head and the other being carried by the tongue and the parts being so proportioned that the spring tongue is operatively engaged with the stop shoulder to hold the shackle against movement when the said two transverse shoulders are in contact. 70

2. In a car seal, in combination, a chambered head having an open end and comprising a base plate and a cover plate having interfolded margins and one of said plates having an outwardly facing transverse shoulder intermediate its ends, a shackle adapted to enter the chamber of the head through its said open end and having a 80 transverse shoulder complementary to the said shoulder on one of the plates of the head and an intermediate plate engageable with the shackle to hold the same within the chamber of the head, the intermediate plate having one of its margins interfolded with the margins of the said base and cover plates at a point beyond the said transverse shoulder on one of the plates of the head from the said open end of the head. 85 90

3. In a car seal, in combination, a chambered head having an open end, one wall of the head being depressed throughout a portion of its length, a tongue formed integral with the wall of the head and being depressed to form a channel throughout a portion of its length, a shackle adapted to enter the head through its open end to engage the tongue, the shackle being of channel shape at the end which enters said head, the depressed portions of the head, tongue and end of the shackle being of complementary form and nested together when the end of the shackle is inserted in the head. 100 95

4. In a car seal, in combination, a continuous strip, adapted to be folded upon itself to form a chambered head and shackle, a plurality of countersunk portions provided throughout the length of the strip, the countersunk portions of the strip when folded being complementary to each other, one of the countersunk portions being provided with a tongue, the shackle having a countersunk end adapted to enter the open end of the head, the shoulders provided by the countersunk portions of the tongue and head forming a step for the shackle and the countersunk part of the shackle forming a closure for the open end of the chambered head. 110 115

5. In a car seal, in combination, a chambered head having an open end, a tongue within the chamber of the head, the point of the tongue being inwardly facing and the tongue being provided with an outwardly facing shoulder, a shackle adapted to enter the chamber of the head provided with a pair of oppositely facing abutment shoulders, one for engaging the point of the tongue and the other for engaging the shoulder on the tongue. 120 125 130

6. In a car seal, in combination, a chambered head having an open end and one wall of the head having an outwardly facing transverse shoulder, a tongue within the 5 chamber of the head the point of the tongue being located beyond the said transverse shoulder from the open end of the head, and a shackle adapted to enter the chamber of the head through its said open end, that part 10 of the shackle which enters the chamber of the head being provided with a pair of oppositely facing transverse abutment shoul-

ders and a longitudinal rib between the shoulders, one of the abutment shoulders of the shackle being engageable with the point 15 of the said tongue and the other abutment shoulder of the shackle being engageable with the said transverse shoulder of the wall of the head.
